(57) **CLAIM**

The ornamental design for a deer feeder, as shown and described.

DESCRIPTION

FIG. 1 is a front perspective view of a deer feeder showing my new design.

FIG. 2 is a fragmented perspective view thereof, for ease of illustration, with the lid in an opened position for clarity of disclosure;

FIG. 3 is a left side elevational view thereof.

FIG. 4 is a right side elevational view thereof.

FIG. 5 is a front elevational view thereof.

FIG. 6 is a rear elevational view thereof.

FIG. 7 is a top view thereof; and,

FIG. 8 is a bottom view thereof.
